(57) **CLAIM**

We claim the ornamental design for a beverage dispenser, as shown and described.

DESCRIPTION

FIG. 1 is an isometric view of a beverage dispenser.

FIG. 2 is a front elevation view of the beverage dispenser of FIG. 1.

FIG. 3 is a rear elevation view of the beverage dispenser of FIG. 1.

FIG. 4 is a right side elevation view of the beverage dispenser of FIG. 1.

FIG. 5 is a left side elevation view of the beverage dispenser of FIG. 1.

FIG. 6 is a top plan view of the beverage dispenser of FIG. 1; and,

FIG. 7 is a bottom plan view of the beverage dispenser of FIG. 1.

The broken lines indicate the bounds of the claimed design and form no part of the claimed design.
